CREEL FOR ANGLERS

Howard L. Domina, Toronto, Ontario, Canada

Application February 7, 1949, Serial No. 731

Term of patent 3½ years

(Cl. D31—4)

To all whom it may concern:

Be it known that I, Howard L. Domina, a citizen of the Dominion of Canada, resident of the city of Toronto, in the Province of Ontario, Dominion of Canada, have invented a new, original, and ornamental Design for a Creel for Anglers, of which the following is a specification, reference being had to the accompanying drawing, forming part thereof.

Fig. 1 is a perspective view of a creel on a reduced scale, showing my new design.

Fig. 2 is an elevation of the creel showing both the cover and the front wall in open positions.

Fig. 3 is a similar view to Fig. 2 but showing the front wall in closed position and the cover in open position.

Fig. 4 is a front view of the creel, depicting the cover in closed position, and

Fig. 5 is an end elevation of the creel.

The characteristic features of my design reside in the portion shown in solid lines.

I claim:

The ornamental design for a creel for anglers, as shown and described.

HOWARD L. DOMINA.
